Specification for Design.

Patented July 23, 1912.

Application filed April 5, 1912. Serial No. 688,767. Term of patent 7 years.

To all whom it may concern:

Be it known that I, CHARLES L. DUENKEL, a citizen of the United States, residing in East Orange, county of Essex, and State of New Jersey, have invented a new, original, and ornamental Design for an Aero-pinwheel, as illustrated in the accompanying drawing.

The drawing herewith illustrates the device in front elevation in Figure 1 and in side elevation in Fig. 2 an aero-pin wheel in

which my novel design is embodied, and such illustration will render the same so clear as to cause any detail description thereof unnecessary.

I claim:

The ornamental design for an aero-pin wheel as shown.

CHARLES L. DUENKEL.
